Primary Examiner — Paula Allen Greene(74) *Attorney, Agent, or Firm* — Faegre Drinker Biddle & Reath LLP(57) **CLAIM**

The ornamental design for the speaker for an automobile as shown and described.

DESCRIPTION

FIG. 1 is a perspective view of a speaker for an automobile showing my new design; and,
FIG. 2 is a front view thereof.

The broken lines depict portions of the speaker for an automobile that form no part of the claimed design.
